UNITED STATES PATENT OFFICE.

HERMANN HILBERT, OF HEUFELD, GERMANY.

METHOD OF MANUFACTURING GLUE AND GELATIN FROM BONES.

No. 833,053.

Specification of Letters Patent.

Patented Oct. 9, 1906.

Application filed January 30, 1905. Serial No. 243,386.

To all whom it may concern:

Be it known that I, HERMANN HILBERT, a subject of the King of Bavaria, residing at Heufeld, Upper Bavaria, in the Kingdom of Bavaria, Germany, have invented certain new and useful Improvements in Methods of Manufacturing Glue and Gelatin from Bones, of which the following is a specification.

I have found that bones contain organic nitrogenous bases or their salts, (picolin and the like,) which are soluble in water and which if not removed before the further treatment of the bones impart to the glue produced from them a disagreeable odor and deteriorate its quality. Besides their bad odor these substances also attract water, which hygroscopic property is also imparted to the glue containing the substances. The before-mentioned bases cannot easily be removed from the coarse-broken bones usually employed in the manufacture of glue. A treatment extending over a comparatively long time (which would be necessary for coarse-broken bones) would cause putrefaction of the glue or gelatin, so that this method cannot be carried through without the employment of an antiseptic, such as sulfurous acid or the like.

I have now found that substances contained in the bones and causing the putrefaction and impairing the quality of the glue and gelatin-like nitrogenous and other acids, bases, or salts of organic or inorganic nature may be easily removed from the bones by washing or filtering the substances with water from the bones, having been ground to a flour, before treating the bones in the usual manner with acids for bleaching and macerating and before boiling them for extracting the glue. My new invention of removing the putrescent substances has the great advantages that the consumption of acids in the following bleaching process and macerating

process is not so great as in my known process cited in my Letters Patent No. 757,685, 45 in which the bones are first of all bleached and macerated and then washed. My new invention results in not only a great economy of chemicals, which are used for the following bleaching and macerating process, but also 50 causes that the treatment of the bones with chemicals to prevent putrefaction is superfluous. This washing process only requires a short time, so that no chemicals to prevent putrefaction need be added, which is a very 55 great advantage, as such chemicals are known to have a very unfavorable influence upon the final product.

According to my improved method it is no longer necessary to employ acids or other 60 chemicals as additions to the glue extracted from the bones. Only when it is desired to obtain colorless glue a small quantity of sulfurous acid may be added to effect the decoloration.

Having now described my invention, what I claim, and desire to secure by Letters Patent, is—

An improved process for manufacturing glue from bones which consists in washing 70 first of all with water from the bones, having been ground to a flour, the putrescent substances, like nitrogenous and other acids, bases or salts of organic and inorganic nature, after which the bone-flour is treated in the 75 usual manner with bleaching agents and macerating agents and boiled for extracting the glue.

In testimony whereof I have hereunto set my hand in presence of two subscribing witnesses.

HERMANN HILBERT.

Witnesses:

ABRAHAM SCHLESINGER,
MATHILDE K. HELD.
